(57) CLAIM

The ornamental design for package, jewelry item, teaching aid, game piece or promotional item, as shown and described.

DESCRIPTION

FIG. 1 is a front view of package, jewelry item, teaching aid, game piece or promotional item showing our new design, the back view being a mirror image thereof;

FIG. 2 is a perspective view thereof from the right and top; FIG. 3 is a perspective view thereof from the right side and front

FIG. 4 is a top view thereof;

FIG. 5 is a bottom view thereof; and,

FIG. 6 is a view thereof from the left and slightly from the top.

The artifact is a solid homogenous convex object. It may take many forms including articles for packaging, articles of decoration and adornment such as sculpture and jewelry, teaching materials, articles for use in games and toys, and articles for use in advertising.
